UNITED STATES PATENT OFFICE.

MARVIN NEWTON, OF GIRARD, PENNSYLVANIA.

WASHING-MACHINE.

SPECIFICATION forming part of Letters Patent No. 377,530, dated February 7, 1888.

Application filed July 18, 1887. Serial No. 244,635. (No model.)

To all whom it may concern:

Be it known that I, MARVIN NEWTON, of Girard, in the county of Erie and State of Pennsylvania, have invented a new and Improved 5 Washing-Machine, of which the following is a full, clear, and exact description.

My invention relates to machines for washing clothes, and has for its object to provide a simple, inexpensive, durable, and efficient 10 machine of this character, which may be worked with little fatigue to the operator and will wash the clothes thoroughly, with economy of time and labor.

The invention consists in certain novel features of construction and combinations of parts of the washing-machine, all as herein- 15 after described and claimed.

Reference is to be had to the accompanying drawings, forming a part of this specification, 20 in which similar letters of reference indicate corresponding parts in all the figures.

Figure 1 is a plan view of my improved washing-machine. Fig. 2 is a central longitudinal section thereof taken on the line $\alpha\alpha$, 25 Fig. 1. Fig. 3 is a transverse section taken on the line $\gamma\gamma$ of Fig. 2. Fig. 4 is a plan view of the rack-bottom of the tub removed therefrom, and Fig. 5 is a bottom plan view of the 30 upper rocking plunger or presser removed from the tub.

The tub A, into which the clothes to be washed and any suitable washing-fluid will be placed, may be supported by legs a, at proper height to allow convenient operation of the 35 machine, in a manner presently explained. Near the bottom of the tub A a rack, B, is pivoted by gudgeons or journals b b to the opposite sides of the tub, so as to have a limited tilting or rocking motion, sufficient to 40 cause the water in the tub to be forced through the clothes, which are placed on the rack and between it and the upper plunger or presser, C, which is journaled by side gudgeons, c c, at the opposite sides of the tub A, and is pro- 45 vided with a handle, D, which projects from one end of the tub to allow a person to grasp its cross-bar d to conveniently operate the machine.

The presser C may be journaled higher or 50 lower in the tub to accommodate varying

quantities of clothes placed between it and the lower rack, B, and as a convenient means of journaling both the rack and presser in the tub an upright bar, E, is fixed to each side of the tub, and to the lower broadened end of this bar E another bar, F, is pivoted, and preferably by the adjacent gudgeons b of the lower rack, B. In the opposing edges of each pair of bars E F, at opposite sides of the tub A, are formed series of semicircular recesses, 60 which, when the bars F are swung over close to the bars E, form journal-bearings f, in any opposite pair of which the journals c c of the presser C may be placed and held by opposite hooks G G, which are pivoted to the bars E 65 and lock over and outside of the bars F. The hooks may be swung upward and the bars F may be swung outward, as indicated in dotted lines in Fig. 2, to allow the presser C to be adjusted higher or lower in the tub. Any suitable clamping devices may be employed to lock the bars E F together for holding the 70 rocking presser instead of the hooks G, above described.

The presser C is made, preferably, in box- 75 like form, open at the bottom, or with a top plate, c', and pendent sides c'', which may be connected by one or more partitions, c'', one longitudinally-ranging partition being shown in the drawings. The journals c c of the 80 presser are formed at the ends of a cross-bar, c', which is fixed to the top plate, c'. In the plate c' there are made holes h, which allow exit of air from the interior of the presser as its ends move or rock downward, and over 85 these holes there are arranged flap-valves H, which close as the ends of the presser move upward and induce a suction below the presser which draws the water through the clothes. The valves H also prevent spattering of water or washing-fluid through the holes h as the machine is in use. A plug, a', fitted in a hole in the tub, may be withdrawn to allow the washing-fluid to discharge from 90 the tub.

The operation, briefly stated, is as follows: After the clothes to be washed are placed upon the bottom rack, B, the presser C will be adjusted in bearings f, so as to press snugly onto the clothes, and the handle D will be worked 95

to rock the presser, which will cause the rack B to rock, also to force the water through the clothes, and as the presser rocks independently of the rack the presser may be rocked as much as may be necessary to squeeze the clothes with requisite force to aid in washing or rinsing them, as the water is forced and sucked through the clothes at every motion of the handle, and the work may be accomplished thoroughly and with economy of time and labor.

A machine constructed substantially as herein described may, with slight modification, be used to advantage as a churn, as will readily be understood.

Having thus described my invention, what I claim as new, and desire to secure by Letters Patent, is—

1. In a washing-machine, the combination, with the tub or tank, of the hollow rocking presser journaled therein and provided with valves in its closed upper end, substantially as set forth.

2. The combination, in a washing-machine, of a tub, a rocking rack or open bottom journaled therein, a rocking presser journaled in the tub above the rocking bottom and made hollow at the under side and provided with air-holes and valves closing said holes to induce suction, and means for rocking the presser and bottom, substantially as described, for the purposes set forth.

MARVIN NEWTON.
